UNITED STATES PATENT OFFICE.

ORESTE BRUNICARDI, OF READING, PENNSYLVANIA.

AEROPLANE.

1,085,968.

Specification of Letters Patent.

Patented Feb. 3, 1914.

Application filed November 16, 1911. Serial No. 660,625.

To all whom it may concern:

Be it known that I, ORESTE BRUNICARDI, a subject of the King of Italy, and a resident of the city of Reading, in the county 5 of Berks and State of Pennsylvania, have invented certain new and useful Improvements in Aeroplanes, of which the following is a specification.

My invention relates to aeroplanes and 10 particularly to emergency appliances thereto, the main object being to provide means for insuring a safe descent of the operator in case of accident to the motor or other essential parts. These attachments consist 15 mainly of additional air contacting extensions which may be spread by the operator, in connection with other features coöperating therewith, as fully set forth in the accompanying drawings and specification, the 20 novel features being particularly pointed out in the subjoined claims.

The drawings are largely diagrammatic and indicate a preferred embodiment of my invention.

25 Figure 1 is a plan view of a biplane aeroplane having my invention applied thereto; the emergency parachute extensions at the front of the machine being shown as spread for emergency use; while those at the rear 30 are shown as actually closed into the upper plane as the front ones are also intended to be when the machine is arranged for normal operation. Fig. 2 is a side elevation, showing both the front and rear parachute extensions as folded-up into the main plane, and the latter in normal operating position. Fig. 3 is a side elevation of the upper plane, indicating the parachute extensions as 35 spread for a safe descent, and the suspended

40 operator's seat in lowered position; the lower plane and the heavy mechanism attached thereto having been detached and dropped to insure safe descent of the operator. Fig. 4 is a similar view of the detached portion 45 of the machine. Fig. 5 is a sectional elevation on the line 5—5 of Fig. 3, the upper plane however being shown in normal flat position as in Fig. 2, while the ridge formation assumed in the emergency position is 50 indicated in dotted lines. Fig. 6 is a sectional elevation on the line 6—6 of Fig. 4. Figs. 7, 8 and 9 are details of the folding parachute extension planes; Figs. 7 and 8 being sectional plan views on the line 7—8 55 of Fig. 9, and showing respectively the closed and open positions of these parachute

planes; and Fig. 9 being a front elevation of the upper plane, showing the folded and locked position of the parachute extensions. Figs. 10 and 11 are details of the upper plane 60 ridge construction; Fig. 10 showing the normal and Fig. 11 the raised position of said ridge, the latter being assumed for emergency use. Fig. 12 is a detail view showing the seat hanging means and the locking device for holding together the upper plane 65 and the machinery frame.

My invention is applicable to machines having one or more supporting planes, but, as shown in the drawings, I have indicated 70 its adaptation to a biplane.

In the drawing 1, 1 indicate the two similar parts or wings forming the upper plane, which parts are hinged at 3, 3 to the longitudinal ridge bar 4. This bar 4 has a limited vertical movement on posts 5 rising from a longitudinal bar 6 carried on the vertical bars 7 of the upper frame, and is secured thereto by locking means hereinafter 75 described.

The lower frame 8 has side planes 9, 9 fixed thereto and arranged substantially parallel with the upper planes 1, 1; and a rigid front extension 11 carries the elevating and depressing device 12, which is pivoted thereto and connected by wires 13 to conveniently located operating means not 80 shown.

The rear extension 14 of frame 8 carries the balancing plane 15, hinged thereto so as 90 to swing vertically, and the rudder 16 arranged to swing in a horizontal plane, both being operable in well known manner. Wheels 17 are provided as usual, to spring bars 18 as shown.

An engine is indicated at 19 and a propeller at 20, both of any well known construction and mounting; and a driver's seat 21 and steering wheel 22 are also indicated.

The machine so far described is operated 100 in well known manner which need not be described.

My improvements are mainly based upon the well known fact that in these heavier-than-air machines, any accident, and especially any trouble with the engine, involves 105 serious danger to the operator; and my object is to provide for insuring his safe descent in case of such accidents.

I will now describe my emergency parachute devices, as shown, and their method 110 of operation.

The upper plane wings 1, 1 have their front and rear edges formed with recesses 23 into each of which parachute extension planes 24 are folded during the normal operation of the aeroplane. Each of these comprises, as indicated, a triangular section of fabric which is secured along one of its edges within one of the recesses 23, and has another of its edges secured to a longitudinally swinging bar 25. This edge bar 25, together with any intermediate-supporting bars 25^a which may be employed, is hinged at one of its ends in the same recess, so that the whole extension plane can be either folded into said recess, and locked therein by a suitable device 26, or can be swung outward therefrom to engage with an extension, 30 or 30^a, of the ridge bar 4. It will be understood that when the four extension planes are thus spread, they will form, in connection with the upper-plane wings 1, 1, an approximately circular parachute of sufficient area to at least insure safety to the operator, as hereinafter fully described, under otherwise hopeless conditions.

The ridge bar extensions, 30 or 30^a, are hinged, as shown, to the main ridge bar 4, and are supported by bracing bars 31, and diagonal stays 35 to the wings 1, 1. Each extension plane 24 is connected to a spring 36 which tends to swing it out of its recess 23 as soon as the catches 26 provided to retain them, are jointly operated to release them; and each is arranged to ride upon a diagonal stay 35, which serves as a guide for a hanger 38 provided on the edge bar 25, until the free outer end of the latter is engaged by a spring catch 39 at the end of the ridge bar extension.

At the same time that the parachute extension planes are released and spread, as just described, provision is made for raising the ridge bar 4 of the upper plane wings so as to give the proper parachute form when thus extended. This is effected by releasing, through connecting wires 40, spring-pressed catches 41 which normally hold said ridge-bar 4 in the lowered position upon the posts 5, indicated in Fig. 10; the released ridge-bar 4 then rising upon the posts 5 to the position shown in Fig. 11, so as to give the concaved form indicated in Fig. 3. As the parachute thus formed cannot be relied upon under all conditions, to insure a safe descent of the disabled machine, owing to the considerable weight of the operating mechanism which is carried, my improvements provide further for dropping the latter, and also for lowering the operator's seat to more favorable position for the parachute descent. For this purpose the vertical bars 7 of the upper frame are engaged in tubular columns 50 of the lower frame, and are normally locked in such engagement by spring catches 51, which latter may be

withdrawn, in case of extreme danger, by means of operating wires 52. The whole lower frame, with its attached mechanism, may thus be dropped by the operator, after the upper plane has been converted into a parachute as already described. When this is done it is desirable that the operator's seat be automatically lowered so as to give greater stability to the parachute in descending; and to this end the seat 21 is specially mounted, as indicated particularly in Fig. 12. The seat frame is normally supported on the lower frame 8, 8^a, by means of its top cross-bar 60, which is seated in open-top bearings 61 formed in the frame 8, and by its forward legs 62 which rest upon the lower cross-bar 8^b, of said frame. Additional flexible connections 63, 64 are provided however, between the seat 21 and the upper frame; so that when the seat drops with the disconnected frame with its attachments, the weight of the seat and of the operator upon it, will be transferred to the upper frame, as indicated in Figs. 3 and 5, and a parachute descent may be safely made.

The advantages of my improvements will be readily understood from the foregoing description; and it will also be readily seen that the construction specifically set forth may be readily modified without departing from the spirit of the invention.

What I claim is:—

1. In an aeroplane having a central longitudinal ridge bar and front and rear extensions thereof, recesses formed in the front and rear edges of said plane, diagonal stays from said ridge bar extensions to said recesses forming guide ways, triangular parachute extensions of said plane secured in said recesses and to spreader arms pivoted in the latter, springs to normally project said spreader arms along said diagonal-stay guide ways, means for normally maintaining said parachute extensions in retracted positions within said recesses, and means for projecting and maintaining the same in extended positions.

2. The combination with an aeroplane comprising a central longitudinal ridge-bar having flexible front and rear extensions, wing planes hinged to said ridge-bar, and retractable front and rear parachute extensions of said wing planes, adapted to engage said ridge-bar extensions, of a supporting frame having guide posts upon which said ridge-bar is vertically movable, and means for normally retaining the latter in lowered position upon said guide posts.

3. The combination with an aeroplane having retractable parachute extensions, of a frame therefor having a separable lower portion, means for securing or releasing said separable portion, and an operator's seat normally supported by said separable

frame portion, but having supplemental connections to the upper frame.

4. The combination with an aeroplane having retractable parachute extensions, of a frame therefor having a separable lower portion, means for securing or releasing said separable portion, and an operator's seat normally supported by said separable frame portion, but having supplemental connec-

tions to the upper frame adapted to carry 10 said seat in lowered position when said separable lower portion of the frame is dropped.

In testimony whereof, I affix my signature, in the presence of two witnesses.

ORESTE BRUNICARDI.
